DESIGN FOR A PERFUME BOTTLE

Stephen A. Ogden, New York, N. Y., assignor to Mary Dunhill, Inc., New York, N. Y., a corporation of New York

Application May 26, 1937, Serial No. 69,557

Term of patent 7 years

To all whom it may concern:

Be it known that I, Stephen A. Ogden, a citizen of the United States, residing in New York, county and State of New York, have invented a new, original, and ornamental Design for a Perfume Bottle, of which the following is a specification, reference being had to the accompanying drawing, forming part thereof.

tle, showing my new design;

Figure 3 is a plan view of the bottle.

I claim:

The ornamental design for a perfume bottle as shown.

STEPHEN A. OGDEN.
